UNITED STATES PATENT OFFICE.

ALBERT BRUCE JOY, OF 26 SAVILE ROW, AND JOHN JOSEPH LEWEN, OF 13 BEAUMONT ROAD, COUNTY OF MIDDLESEX, ENGLAND; SAID LEWEN ASSIGNOR TO SAID JOY.

PROCESS OF TREATING PLASTER CASTS.

SPECIFICATION forming part of Letters Patent No. 317,369, dated May 5, 1885.

Application filed January 3, 1885. (No specimens.) Patented in England October 31, 1884, No. 14,430.

To all whom it may concern:

Be it known that we, ALBERT BRUCE JOY and JOHN JOSEPH LEWEN, both subjects of Her Majesty the Queen of Great Britain, residing, respectively, at 26 Savile Row and 13 Beaumont Road, in the county of Middlesex, England, have invented a certain new and Improved Process of Treating Plaster Casts, of which the following is a specification.

10 The object of this invention is to so treat plaster casts as to give them the appearance of marble; and to this end our invention consists in submerging the dry plaster casts in a bath of refined linseed or other suitable oil 15 for a period of six or seven days. The casts are then removed from the bath and allowed to stand in a warm place for a period of, say, four to five days, after which they receive a thin coating of flake-white mixed with refined 20 linseed or other suitable oil or spirit.

Instead of the flake-white, zinc or other white may be employed; but by experiment we find that the flake-white gives good results.

25 If it be desired to give the casts the appearance of new marble, finely-flaked mica may be brushed on lightly over the final coating of flake or other white. This mica coating need not be employed except it is desired 30 to produce an imitation of speckled marble.

We are aware that it is not new to bronze ornaments composed of plaster-of-paris, wood, iron, &c., with varnish of different colors to protect them from the action of the weather; and

35

What we therefore claim, and desire to secure by Letters Patent, is—

1. The improved process of treating plaster casts, which consists in first submitting them to the action of an oil bath, then drying and 40 subsequently coating them with flake or other suitable white, substantially as described, and for the purpose set forth.

2. The improved process of treating plaster casts, which consists in first submitting them 45 to the action of an oil bath, then drying, then coating with a flake or other suitable white, and subsequently brushing them over lightly with finely-flaked mica, substantially as described, and for the purposes set forth.

ALBERT BRUCE JOY.
JOHN JOSEPH LEWEN.
